UNITED STATES PATENT OFFICE.

PAUL M. RAINIER, OF WEST HOBOKEN, NEW JERSEY, ASSIGNEE TO WESTERN ELECTRIC COMPANY, INCORPORATED, OF NEW YORK, N. Y., A CORPORATION OF NEW YORK.

SELECTING SYSTEM.

1,303,496.

Specification of Letters Patent. Patented May 13, 1919.

Application filed February 10, 1917. Serial No. 147,800.

To all whom it may concern:

Be it known that I, PAUL M. RAINIER, a citizen of the United States, residing at West Hoboken, in the county of Hudson and State of New Jersey, have invented certain, new and useful Improvements in Selecting Systems, of which the following is a full, clear, concise, and exact description.

This invention relates to selecting systems of an electro-mechanical type, particularly adapted for use in printing telegraphs where tape transmission is employed, although obviously not limited to such use.

One of the principal objects of this invention is to provide a two-way simplex system, or one providing two channels over a single wire, without the use of duplex balance.

Another object is to provide a system of the above type wherein the same electro-mechanical devices may be utilized for transmitting and receiving selecting current impulses.

A further object is the provision of means for causing the movable parts, located at different stations, to operate substantially in synchronism or unison, without the use of synchronizing apparatus.

For the accomplishment of the above objects, the invention contemplates the use of an electromechanical reciprocating device, arranged to co-operate with a current controller, to form current impulses for the line, and to co-operate with a selecting mechanism to distribute the effects of current impulses from over the line. In combination with the above apparatus, means are provided for causing said reciprocating device to alternately associate the line with the current controller and selecting mechanism, whereby each station alternately acts as a transmitter and a receiver.

The above and other objects of this invention will be fully set forth in the following description and claims, and will be more readily understood by reference to the accompanying drawing in which is disclosed one specific embodiment, particularly adapted for use in printing telegraphs.

The system of this invention is here shown as adapted for use with the well-known Baudot code of five positive and negative impulses, using, however, an additional impulse for operating a starting magnet. Obviously, other codes may be used

without departing from the spirit of this invention. The system preferably requires but a single line conductor with a ground return. It is readily apparent, from the accompanying drawing, that either station A or B may be used as a transmitter, a receiver or a combined transmitter and receiver. The apparatus used at the two stations and the circuits therefor are identical.

When used as a transmitter, the movable contacts 1, 2, 3, 4 and 5 of the current controller 25 may be selectively operated by means of any convenient apparatus, as, for example, selecting keys arranged in the form of an ordinary typewriter keyboard, or an automatic mechanism controlled by a perforated tape or the like. Movable contacts 1 to 5, inclusive, are permanently connected to sending segments 11, 12, 13, 14 and 15, respectively, and are normally connected to negative battery 33, but, when operated or moved to the left, are connected to positive battery 32. The distributor arm 16 is pivoted at 17, and consists of two current conducting members 18 and 19 insulated from each other. One end of member 18 is formed into a brush-like member 45, which is adapted to pass over and make contact with the sending segments 11 to 15, inclusive, and the other terminal is arranged to connect with the line L through contact 20. One end of member 19 is arranged to be connected through contact 21 to armature 22 of the polar line relay 23, and the other end is, formed into a brush-like member 46, which is adapted to pass over and make contact with the receiving segments 26, 27, 28, 29 and 30, which are connected to selecting magnets 36, 37, 38, 39 and 40, respectively. The selecting magnets 36 to 40, inclusive, may operate an electrical printer or any suitable recording apparatus.

The distributor arm 16 is arranged to be operated in a reciprocatory manner by means of a pair of sending and receiving distributor magnets 41 and 42, which, when energized, act upon the common armature 43, and, by means of the connecting link 44, move the distributor arm brushes back and forth across the sending and receiving segments. The distributor magnets 41 and 42, acting through the distributor arm, also control a plurality of contact members 50, 51, 52 and 53, the purpose of which will be explained hereinafter.

- A better understanding of the system can be obtained from the description of the selection of a specific character, and the various operations which take place in transmitting and receiving the necessary impulses for representing a given character. Assume that the system, as shown, is in operation, and that the distributor arm 16 is just starting to move to the right under the influence of the distributor magnet 42, current for which is being supplied from battery 55. Assume also, for example, that impulses for effecting the printing of the letter "D" are to be transmitted from station A to station B, and that the combination of impulses required is positive, negative, negative, positive, negative. The depression of the "D" key of the keyboard or the passage of a perforated tape through an automatic transmitter with perforations therein, representing the character "D", will transfer the movable contacts 1 and 4 from negative to positive battery. It will also move contact 6 into engagement with contact 7, and thereby effect the energization of the transmitter magnet 9, which magnet will hold the selected contacts in their moved positions, and will remain energized until it is short-circuited, as will be hereinafter explained.
- Contacts 6 and 7 are closed upon the operation of each key, or the setting up of each selection. As soon as the distributor arm 16 has been moved sufficiently far to bring the brush 45 into engagement with segment 10, a circuit is completed from positive battery 32, segment 10, brush 45, member 18, contact 20, contact member 58, line L, contact member 158, contact 160 through polar line relay 123 to ground. Relay 123 pulls up its armature, thereby completing a circuit from grounded battery 165, armature 122, contact 121, member 119, brush 146, segment 131 and starting relay 166 to ground. Relay 166 immediately pulls up its armature 137, thereby completing a temporary holding circuit for itself from battery 168, contact member 152, distributor magnet 141, key 169 and contact thereof, armature 167 and relay 166 to ground. This causes the distributor magnet 141 to attract armature 144, and through the connecting link 144, move distributor arm 116 to the left. Now the distributor arm 16 is moving to the right while the distributor arm 116 is moving to the left, and, as the brush 45 passes over the sending segment 11, the brush 148 will pass over the corresponding receiving segment 130. Since the first impulse is of positive polarity, the polar line relay 123 will be operated to connect the armature 122 with contact 121, and thereby complete a circuit from battery 165, armature 122, contact 121, member 119, brush 146, segment 130, selecting magnet 140 to ground. Selecting magnet 140 will be operated, and may move a disk or perforated
- card function by connecting with, according to the character which is being transmitted. The distributor arm 16 will continue to move to the right, and brush 45 will pass over sending segments 12, 13, 14 and 15, while to the distributor arm 116 moves to the left, and the brush 148 passes over receiving segments 152, 153, 154 and 155, respectively. The line relay 123 is biased so that the armature 122 is normally set at disengagement with the contact 121, and is moved into engagement with contact 121 only upon receipt of positive impulses. Since the second and third impulses are of negative polarity, line relay 123 and starting magnet 160 will not be operated. The fourth impulse, being of positive polarity, will cause the armature of line relay 123 and in moving along not 137 in the same manner as the previous impulse of positive polarity, effect the re-engagement of the line relay and selecting magnet 140. Since the fifth impulse is of negative polarity, selecting magnet 123 and selecting magnet 140 will not be operated.
- The distributor arm 16 has now moved to the extreme right against back stop 76, so that the brush 45 has passed off of segment 15, and brush 148 now rests on segment 161. The distributor arm 116 has now moved to the extreme left against back stop 71 and is out of engagement with the sending and receiving segments. Distributor arm 16, operating with the current contacts 121, has impressed upon the line a series of alternating impulses, and each of these impulses, along with the first, second and third negative impulses, is of such short duration as to permit of a rapid and accurate transmission.
- The distributor arm 16, just before reaching the back stop 76, but after brush 45 has passed off of nearly all of segment 15, engages a pin 74 and causes the slide bar member 75 to move to the left, thereby moving contact members 52 and 53 to the left, as is clearly shown in the drawing, at section 31. The movement of the member 75 to the left also permits contact member 50 to disengage its last contact and thereby open the over-current circuit for the distributor magnet and contact member 45, when moved into engagement with contact 73 by reason of the arm 116, short-circuiting the brush 148, member 53, thereby permitting its armature to fall off and restore the moved contacts 1 and 2 to normal, and open the common contacts 6 and 7. This arrangement permits a new selection to be set up while the distributor arm is moving from the right-hand to the left-hand position and the brush 45 is brought into engagement with sending segment 11 on its forward movement to the right. It will be noted that contacts 51 and 73 are closed only immediately while the distributor arm is in the ordinary right-hand position.

position. The movement of contact member 52 to the left partially prepares an energizing circuit for the distributor magnet 41 which is not completed until the starting relay 66 is energized to bring armature 57 into engagement with its front contact. Contact member 53, in moving to the left, disengages contact 20, thereby disconnecting the sending brush 45 at station A from line L, and 10 engages contact 60, thereby connecting the line L to the polar line relay 23, ready to receive impulses from station B. Current from battery 80 flows through the line relay 23 to hold it in its biased position while station A is acting as a transmitter, and is disconnected from the line relay by opening of contact 31 while station A is receiving.

The apparatus at station A is precisely the same and functions in precisely the same manner as the apparatus at station B. Therefore, only so much of the apparatus is herein described as is essential to a clear understanding of the system. The apparatus at either station may be used to transmit, receive, or transmit and receive alternately.

The apparatus and the manner in which the apparatus functions, when the system is operated, have been described. Means whereby the operators at either station may 20 stop or start the apparatus at will, independently of the operator at the other station, will now be described.

Each operator is provided with a switch or key, which may be opened momentarily for 25 stopping the apparatus at both stations. Assume, for example, that the operator at station A desires to stop the apparatus. He will open the switch 69, thereby opening the energizing circuit of distributor magnet 41, and the distributor arm 16 will stop in the 30 position shown in dotted lines, and both distributor arms will rest against their respective right-hand back stops. Even though the switch 69 be again closed, magnet 41 will 35 not be energized because the circuit therefor is opened at the contact of armature 67 of starting relay 66, and both distributor arms will remain at rest.

Now assuming that the operator at station 40 A or B desires to start the apparatus. This may be accomplished by the momentary closure of switch 79 or switch 179. Assume the operator at station A closes the switch 79; a 45 circuit will be completed from battery 68, contact member 52 (which is now in engagement with the back contact thereof), winding of magnet 41, switch 69, switch 79, and winding of starting relay 66 to ground. The starting relay 66 will pull up its armature 50 and complete a temporary holding circuit for itself through armature 67 and contact thereof, and magnet 41 will attract the armature 48 and move the distributor arm 16 to the left. The apparatus has now been set in motion, and will continue to operate until the 55

switch 69 or switch 169 is opened, thereby opening the energizing circuit for the distributor magnet 41.

What is claimed is:

1. In a selecting system, the combination 70 of a transmission line and a station at each end thereof, a reciprocating brush carrying distributor at each station for transmitting and receiving groups of signaling impulses, an electromagnet for operating said distributor, and means at each station for controlling the distributor at the other station whereby said distributors operate substantially in unison.

2. In a selecting system, the combination 80 of a transmission line and a station at each end thereof, each station comprising a distributor having a plurality of conducting segments, electromagnets for operating said distributor to effect the transmission of successive groups of signaling impulses, a device actuated by said distributor for controlling the said electromagnets, and means for influencing the said distributor at the other station to provide mutual control 90 whereby said distributors operate approximately in unison.

3. In a selecting system, the combination 95 of a transmission line, a pair of sets of transmitting and receiving segments one set at each end of said line, a reciprocating brush carrying device cooperating with each set of said segments, a magnet for moving said brush carrying device in one direction, a second magnet for moving said brush carrying device in the opposite direction, and means associated with each set of said segments for controlling the action of said mechanism located at the other station whereby mutual control exists between said 105 devices.

4. In a selecting system, the combination 110 of a transmission line and a station at each end thereof, each station comprising a current controller, selecting mechanism, a distributor adapted to cooperate with said controller and said mechanism to form current impulses for said line and to distribute the effects of current impulses therefrom, apparatus for causing said distributor to alternately associate said line with said controller and said mechanism whereby each station alternately acts as a transmitter and a receiver, an electroresponsive device for influencing said apparatus to cause said distributor to operate approximately in synchronization, and means associated with said distributor for affecting the said device at the other station.

5. In a selecting system, the combination 125 of a transmission line and a station at each end thereof, each station comprising a current controller, selecting mechanism, a distributor adapted to cooperate with said controller and said mechanism to form current 130

impulses for said line and to distribute the effects of current impulses therefrom, apparatus for causing said distributor to alternately associate said line with said controller and said mechanism whereby each station alternately acts as a transmitter and a receiver, and means for influencing said apparatus at the other station to cause said distributor to operate approximately in synchronism.

6. In a selecting system, the combination of a transmission line and a station at each end thereof, each station comprising a current controller, selecting mechanism, a distributor adapted to cooperate with said controller and said mechanism to form current impulses for said line and to distribute the effects of current impulses therefrom, apparatus for causing said distributor to alternately associate said line with said controller and said mechanism whereby each station alternately acts as a transmitter and a receiver, an electroresponsive device for in-

fluencing said apparatus to control the starting and stopping of said distributor, a source of current, and a contact to enable distributor to receive said current so that the said device at the other station may produce mutual control whereby said distributor operates approximately in synchronism.

7. In combination, a distributing system comprising current controller, selecting mechanism, a distributor, apparatus for influencing said apparatus to control the starting and stopping of said distributor, a source of current, and a contact to enable distributor to receive said current so that the said device at the other station may produce mutual control whereby said distributor operates approximately in synchronism.

In witness whereof, I have this day of January, 1917.

WILLIAM H. HARRIS
